UNITED STATES PATENT OFFICE.

JOHN F. ROGERS, OF CLEVELAND HEIGHTS, OHIO, ASSIGNOR TO THE WELLMAN-SEAVER-MORGAN COMPANY, OF CLEVELAND, OHIO, A CORPORATION OF OHIO.

GAS PRODUCER.

Application filed December 26, 1918. Serial No. 268,293.

To all whom it may concern:

Be it known that I, JOHN F. ROGERS, a citizen of the United States, residing at Cleveland Heights, in the county of Cuyahoga and State of Ohio, have invented a certain new and useful Improvement in Gas Producers, of which the following is a full, clear, and exact description.

The object of this invention stated generally is to provide a mechanical gas producer which will operate with a high degree of efficiency and with a minimum of attention.

Another object of the invention is to minimize, as much as possible, the formation of clinkers in the producer proper, and to insure such a breaking up and crushing of the clinkers in the ash pan as is necessary for the efficient operation of the machine.

Another object of the invention is to insure the automatic withdrawal of ashes from the ash pan at a suitable rate which may be varied according to requirements.

The producer shown in the drawing embodies the various improvements which contribute to the production of the stated results; and the invention consists of the combinations of parts as set forth in the appended claims.

In the drawing, Fig. 1 is an elevation of the producer; Fig. 2 is a central vertical section of the producer; Fig. 3 is a top view of the producer, and Fig. 4 is a horizontal section in the plane of line A—B on Fig. 2.

The producer includes a non-rotating top 10 which is supported on a plurality of columns 26, 26^a; and in turn supports certain parts and mechanisms to be hereinafter referred to.

Below this top is a rotatable producer body, and various associated parts which are so connected with the producer body that they produce a single rotating unit.

At the top of the producer body is an annular water sealing pan 13, and into this projects an annular sealing flange 10^a which is a part of the top 10.

Below the rotating producer body is a co-axial rotatable ash pan into which the ash hopper 14 projects,—said ash hopper being fixed to the producer body.

The rotatable unit of which the producer

body is a part includes a sheet metal shell 15^a having a fire brick lining 15^b; a hollow blast ring 16 forming a wind box which is 55 provided with apertures 16^a through which air is discharged into the lower portion of the producer body and which is secured to the lower end of the shell 15^a, and helps to support the fire brick lining; a spider comprising a tapered ring 18 forming a portion of the wall of the producer body which is fixed to the lower side of the blast ring 16, a hollow hub 18^a, and a plurality of (preferably three) hollow blast arms 18^b 65 which connect the hub 18^a and the ring 18; and which at their outer ends communicate with the blast ring 16 through apertures 16^b; a hollow blast column 19 to the upper end of which the hollow hub 18^a is securely 70 fixed, and with which it is in open communication;—said blast column having an outwardly projecting base 20 by means of which the described rotatable unit is supported upon a track ring 21, the top surface 75 of which is obliquely conical, and fitted to the wheels 22 which are mounted upon the base 20 and ride upon this track; and a tapered apron 14 forming the ash hopper fixed to the lower edge of the ring 18. 80

A blast hood 17 is secured upon the hollow hub 18^a over an opening 18^c in the upper end thereof. A gear ring 23 is fixed to the base 20 and this is in mesh with a driving pinion 24 whereby the rotatable unit 85 is turned. This pinion 24 is the lower terminal member of a train 27 of reducing gears, by which power is transmitted from a motor 28 that may be mounted on one of the columns 26.

A blast pipe 29 discharges centrally into the lower end of the blast column 19. It carries at its upper end a deep water sealing pan 30; and the blast column carries a cylindrical flange 31 which extends downward 95 into said sealing pan.

40 represents an annular ash pan having upwardly diverging outer and inner walls. A sleeve 41 is formed on the upper edge of the inner wall, and this sleeve is rotatably fitted around the blast column 19, just below the spider hub 18^a. The location of the ash pan is such that the ash hopper apron 14 projects down into it. The inclination of

the outer wall of the ash pan substantially corresponds with and is therefore substantially parallel with this ash hopper apron 14.

This ash pan is rotatably supported upon 5 the blast column base 20 through coned wheels 42 mounted on the base, and an obliquely coned track 43 in the bottom of the ash pan which is fitted to ride on said wheels.

10 On the bottom of the ash pan also is formed a bevel gear ring 44. A bevel pinion 45 is in constant mesh with this gear, said pinion being fixed to a shaft 46 which is mounted in bearings secured to the gear ring 23. A star wheel 48 is secured to the outer end of shaft 46 in such position that, as the gear ring 23 is rotated, this star wheel will periodically come into engagement with one or more pins 49 fixed to one 15 or more of the standards 26, 26^a, and be turned thereby.

From the foregoing it will appear that there is no mechanical connection between the ash pan and the rotating unit of which 20 the producer body is a part which necessarily compels them to rotate in unison. They are capable of independent rotation about the same axis. Normally they rotate in unison or in substantial unison. This 25 being due primarily to the fact that the ash pan is supported on the base or lower part of the rotatable unit, which when the producer is in operation is positively and continuously rotated. Additionally the column 30 of ashes supported by the ash pan and extending upward therefrom into the producer body would tend to cause the ash pan to rotate in substantial unison with the producer body. Every time, however, that the 35 star wheel 48 engages one of the pins 49 the ash pan will be turned relatively to the producer body. It is thus turned backward relative to the producer body but since the star wheel 48 and pinion 45 are carried by 40 the rotating gear 23, the effect of the periodic turning of the pinion 45 is to periodically reduce or slow down the rotation of the ash pan. In other words, though the ash pan normally rotates in unison or substantial unison with the producer body, it is caused automatically and intermittently or at intervals to rotate slower or to lag with respect to the producer body. Obviously, therefore at intervals one part goes 45 a definite or predetermined amount faster than the other. This relative movement of the ash pan and the hopper apron 14 which is formed with vertically disposed ribs or corrugations will cause the column of ashes supported by the ash pan to twist relatively to the material within the producer body, thereby disintegrating the clinkers and preventing in a large degree the formation of pipes within the fuel.

50 On the inner face of the inner wall of the

ash pan are a plurality of spirally inclined wings 52 which extend from the top to the bottom of the ash pan. The shape of these wings is such that as the ash pan is turned relatively to the producer these wings will force the ashes in the ash pan downward and cause them to flow beneath the lower edge of the apron 14.

An inclined plow 60 which is mounted on one of the columns 26^a projects down into the ash pan between the outer wall thereof and the apron 14. Therefore, while the ash pan is turning the ashes will be forced up this inclined plow and into a laterally extended spout 12 which extends over the top of the outer wall of the ash pan.

The plow 60 is fixed to a bracket 26^b which in turn is fixed to one of the standards 26^a. The lower end 60^a of the plow is slideable up and down upon the main body thereof, toward and from the bottom of the ash pan, whereby the rate of discharge of ashes through the action of this plow may be varied as required. This adjustment is effected by means of a screw 60^b which is mounted in bearings in the bracket 26^b, and screws into the adjustable lower end 60^a of the plow. On its upper end this screw has a beveled gear 60^c which meshes with a bevel gear 63, and this in turn meshes with a bevel gear 64, fixed to the lower end of a rotatable shaft 65 which has a hand wheel 66 at its upper end, by which this screw may be turned, and the adjustable lower end of the plow raised or lowered as required.

The fixed top 10 has through it a hole 70 for the discharge of the gas produced in the producer body. It likewise supports a fixed fuel feeding device 71 by means of which measured quantities of fuel may be periodically discharged into the producer so as to substantially maintain the desired fuel level therein. Any suitable fuel feeding device, of which many varieties are known, may be employed for this purpose, although preference is given to the device which is shown in outline in Figs. 1 and 2, and is shown in detail and clearly described in my Patent No. 1,331,785, Feb. 24, 1920. This top 10 also furnishes the bearings for a plurality of producer steadyng wheels 74 that engage a ring 13^a at the upper end of the producer body.

This top 10 also supports two rock shafts 80, 81; and to these rock shafts the pokers 82, 83, are respectively secured. The parts of the rock shafts to which these pokers are secured are within chambers 84, fixed to the top 10 and opening only into the producing body. These pokers are of different lengths, and therefore extend down into different zones of fuel in the producer body, and are therefore capable of performing different but important functions when the producer body is being operated with a deep fuel

bed, the level of which is substantially indicated by the line 77 for the production of byproduct gas. The long poker 82 extends down into the incandescent zone near the bottom of the producer body; but the short poker 83 extends into what will then be the caking zone of the fuel bed. When this producer is operated for the production of ordinary producer gas, the fuel level in the producer is kept at about the point indicated by the line 78, in which case the shorter poker is unnecessary because it performs no function.

On the ends of the two shafts 80, 81, which extend out of the said chambers, operating arms 86, 87, are respectively secured, and these arms are respectively connected to eccentric straps 88, 89, which embrace and extend from eccentrics 90, 91, fixed to a shaft 92, which is also mounted on the top 10, these eccentrics being so placed that as said shaft turns the pokers are rocked in opposite directions. This shaft 92 carries a ratchet 93. It likewise supports a rocking plate 94 which carries pawls 95 for engagement with said ratchet. The plate 94 is connected by a rod 96 with a crank 97 carried by the shaft 99 of one of the gears of the gear train 27. It is evident, therefore, that the rocking action of the pokers may be properly synchronized with respect to the rotation of the producer.

Having described my invention, I claim:

1. In a gas producer, the combination of a rotatable producer body having at its lower end a tapered ash hopper, means to rotate said producer body, a coaxial ash pan located below the producer body in such position that the lower part of the ash hopper projects into it, a mechanism which as the producer body and ash pan are turning will act automatically at predetermined intervals and compel the ash pan to turn a short distance at a different rate from that at which the producer body is turned.

2. In a gas producer, the combination of a revoluble producer body having an ash hopper fixed to and depending from said body, a rotatable ash pan which is disposed below and coaxially with said producer body and into which said ash hopper projects, means for continuously rotating the producer body, and automatic means acting upon the ash pan periodically to prevent the producer body and ash pan from rotating in unison, an inclined plow which projects into the ash pan between the outer wall thereof and said ash hopper, means for adjusting said plow toward and from the bottom of the ash pan.

3. In a gas producer, the combination of a rotatable producer body, an independent rotatable annular ash pan having upwardly diverging inner and outer walls, which ash

pan is disposed below and coaxially with respect to said producer body, an ash hopper fixed to said producer body and extending therefrom down into the ash pan, spiral wings in the ash pan fixed to the inner wall thereof, an inclined plow which projects into the ash pan between the outer wall and the ash hopper, and automatic means which act periodically to positively turn the ash pan relatively to the producer body.

4. In a gas producer, the combination of a fixed top, a rotatable unit comprising a blast column having a supporting base, a spider fixed to said blast column, and having hollow arms which communicate with said blast column, an annular wind box which is supported by said spider and into which said blast arms discharge, and a producer body secured upon said wind box, said wind box having apertures discharging into said producer body, an independently rotatable annular ash pan which surrounds said blast column, means to rotatably support the ash pan, and means to occasionally turn the ash pan relatively to said rotatable unit.

5. In a gas producer, the combination of a rotatable producer body, means for rotating it, a coaxial blast column below said producer body, means through which said blast column discharges its blast into said producer body, and an independently rotatable annular ash pan which is located below said producer body and which surrounds and has a rotatable engagement with said blast column, means for rotatably supporting said ash pan, an ash hopper fixed to the producer body and projecting into said ash pan, and automatic means to periodically turn the ash pan relatively to said producer body.

6. In a gas producer, the combination of a rotatable producer body, means for rotating it, a coaxial blast column below said producer body, means through which said blast column discharges its blast into said producer body, an independently rotatable annular ash pan which is located below said producer body and which surrounds and has a rotatable engagement with said blast column, means for rotatably supporting said ash pan, an ash hopper fixed to the producer body and projecting into said ash pan, automatic means to periodically turn the ash pan relatively to said producer body, and an inclined plow which projects into the ash pan outside of said ash hopper.

7. In a gas producer, the combination of a rotatable producer body which is provided near its lower end with an annular wind box which forms a part of the wall of the producer body, a spider comprising a ring which is secured to the wind box, a hollow central member and a plurality of hollow arms extending therefrom to said ring and communicating with said wind box, a hol-

low blast column to the upper end of which said spider is attached, an outwardly extended base rigid with said blast column, an ash hopper secured to the ring of said spider, an annular supporting track, and rollers interposed between said track and the base of said blast column whereby the unitary structure referred to is supported, an annular ash pan which is rotatably mounted upon said blast column in such position that the ash hopper referred to projects into it, rollers supporting said ash pan and interposed between it and the base of said blast column, means for rotating the producer body, and means for turning the ash pan periodically relatively to the producer body.

8. In a gas producer, the combination of a rotatable producer body having near its lower end an annular wind box which forms a part of the wall of the producer body, a spider comprising a ring which is secured to the wind box, a hollow central member, and a plurality of hollow arms extending therefrom to said ring and communicating with said wind box, a hollow blast column to the upper end of which said spider is attached, an outwardly extended base rigid with said blast column, an apron secured to the ring of said spider, an annular track, and rollers interposed between said track and the base of said blast column whereby the structure referred to is supported, an annular ash pan which is rotatably mounted upon said blast column in such position that the ash hopper referred to projects into it, the rollers supporting said ash pan and interposed between it and the base of said blast column, means for rotating the producer body, a gear ring fixed to the ash pan, a shaft mounted on the base of the blast column, a pinion fixed to said shaft engaging said gear ring, a star wheel fixed to said shaft, and a fixed pin located in position to be engaged by said star wheel during the rotation of said ash pan.

9. In a gas producer, the combination of a rotatable producer body, a concentric rotatable cylindrical hollow blast column, means operating on one of said members to turn it, means connecting said members to compel them to rotate in unison, an ash pan which rotatably surrounds the blast column, and means to periodically prevent the ash pan from rotating in unison with the producer body and blast column.

10. In a gas producer, the combination of a rotatable producer body, a concentric rotatable cylindrical hollow blast column, means operating on one of said members to turn it, means connecting said members to compel them to rotate in unison, an ash pan which rotatably surrounds the blast column, and automatically acting means to periodically prevent the ash pan from rotating in

unison with the producer body and blast column.

11. In a gas producer, the combination of a rotatable producer body, a concentric cylindrical hollow blast column which has at its lower end a base, means engaging said base by which the blast column is rotatably supported, means operating on the base to turn it, means connecting said blast column and producer body to compel them to rotate in unison, an ash pan which is rotatably supported upon said base and which is formed with a sleeve which rotatably surrounds the hollow blast column, and automatic means acting periodically to prevent the ash pan from rotating in unison with said blast column.

12. In a gas producer, the combination of a vertical hollow blast column having a base, means by which said base is rotatably supported, a producer body having a connection with said hollow blast column whereby the body and column rotate in unison, an ash pan which is rotatably supported upon the base of said blast column and has a sleeve that rotatably surrounds the hollow blast column, and an annular gear upon its bottom, a shaft rotatably supported by the base of said blast column having a pinion which engages said gear, a star wheel fixed to said shaft, and a fixed pin located in position such that it will be engaged by said star wheel as the blast column rotates.

13. In a gas producer, the combination of a rotatable producer body having at its lower end a corrugated hopper shaped apron, a rotatable ash pan supported below said producer and into which said apron projects, said ash pan having oppositely inclined inner and outer walls, means for turning the producer body, and means to periodically prevent the ash pan and producer body from rotating in unison.

14. In a gas producer, the combination of a rotatable producer body having at its lower end a corrugated hopper shaped apron, a rotatable ash pan supported below said producer and into which said apron projects, said ash pan having oppositely inclined inner and outer walls, means for turning the producer body, means to periodically prevent the ash pan and producer body from rotating in unison, spiral rings fixed to the inner inclined wall of said ash pan, and a plow projecting into said ash pan into the space between the outer inclined wall of the ash pan and the inclined hopper.

15. In a gas producer, the combination of a rotatable producer body, an annular wind box located near the lower end of said producer body and rotating therewith, a hollow central member, a plurality of hollow arms extending therefrom and communicating with said wind box, a rotatable hollow blast column the upper end of which communi-

- 12 cates with said hollow central member, and
13 an ash pan located adjacent the lower end of
14 said producer body and adapted for relative
15 rotation with respect thereto.
- 16 16. In a gas producer, the combination of
17 a rotatable producer body, an annular wind
18 box carried by and located near the lower
19 end of said producer body, a hollow central
20 member, a plurality of hollow arms extending
21 therefrom and communicating with said
22 wind box, a rotatable hollow blast column
23 the upper end of which communicates with
24 said hollow central member, a rotatable ash
25 pan located adjacent the lower end of said
26 producer body, means for rotating one or
27 of said rotatable parts at a predetermined speed
28 and means for causing the other of said
29 rotatable parts to rotate at a different speed.
- 30 17. In a gas producer, a producer body
31 and an ash receptacle beneath the same, both
32 rotatably mounted, and motion imparting
33 and controlling means which when the pro-
34 ducer is in operation causes both parts to
35 rotate in unison and automatically and in-
36 termittently causes one of said parts to lag
37 with respect to the other whereby a pre-
38 determined relative rotation between the
39 parts is effected.
- 40 18. In a gas producer, a producer body
41 and an ash receptacle beneath the same, both
42 rotatably mounted, and motion imparting
43 and controlling means which when the pro-
44 ducer is in operation causes both parts to
45 rotate in unison and at each revolution of
46 the producer body automatically causes the
47 producer body to rotate relative to the ash
48 receptacle.
- 49 19. In a gas producer, a producer body
50 and an ash receptacle beneath the same both
51 rotatably mounted, and motion imparting
52 and controlling means which when the pro-
53 ducer is in operation causes a continuous
54 regular motion to be imparted to one part
55 and automatically causes a definite intermit-
56 tent motion to be imparted to the other part.
- 57 20. In a gas producer, a producer body
58 and an ash receptacle beneath the same both
59 rotatably mounted, and movement imparting
60 and controlling mechanism for causing
61 both parts to rotate when the producer is
62 in operation and operating automatically to
63 cause one part to make a greater number of
64 revolutions than the other in a given time.
- 65 21. In a gas producer, a producer body, an
66 ash receptacle beneath the same, both of
67 said parts being rotatably mounted, means
68 for applying motion so as to cause the rota-
69 tion of both said parts when the producer
70 is in operation, and automatically operating
71 means for causing one of said parts to turn
72 in definite relation to the other.
- 73 22. In a gas producer, a producer body,
74 an ash receptacle beneath the same, both said
75 parts being rotatably mounted, means for
76 applying motion so as to cause the rotation
77 of both of said parts when the producer is in
78 operation, and automatically operating means
79 for periodically varying the rotation of one
80 of said parts so as to cause a relative rota-
81 tion between the two parts.
- 82 23. In a gas producer, a rotatable producer
83 body, a rotatable ash receptacle beneath the
84 same, means for rotating one of said parts
85 whereby the other will be rotated, and means
86 for automatically and at substantially regu-
87 lar intervals causing a relative rotation be-
88 tween said parts.
- 89 24. In a gas producer, a rotatable producer
90 body, a rotatable ash receptacle beneath the
91 same, means for positively and continuously
92 rotating the producer body whereby the ash
93 receptacle will be rotated in unison or sub-
94 stantial unison therewith, and automatic
95 means to periodically prevent the ash pan
96 from rotating in unison with the producer
97 body.
- 98 25. In a gas producer, a rotatable producer
99 body, a rotatable ash receptacle beneath the
100 same, means for rotating the producer body
101 whereby the ash receptacle will be rotated in
102 unison or substantial unison with the pro-
103 ducer body, and automatic means acting at
104 intervals to cause the ash pan to make less
105 than one revolution while the producer body
106 is making one complete revolution.
- 107 26. In a gas producer, a rotatable producer
108 body, a rotatable ash receptacle beneath the
109 same, means for rotating the producer body
110 whereby the ash receptacle will be rotated
111 in unison or substantial unison with the pro-
112 ducer body, and automatic means acting to
113 periodically cause the ash receptacle to have
114 a retarded rotation relative to the rotation
115 of the producer body.
- 116 27. In a gas producer, a rotatable producer
117 body having at its lower end a hopper
118 shaped apron, an ash receptacle beneath the
119 producer body into which said apron pro-
120 jects, and means for rotating the producer
121 body and for causing the producer body to
122 rotate relative to the ash receptacle, the por-
123 tion of the apron within the ash receptacle
124 having laterally projecting ash engaging
125 means which exerts a disintegrating action
126 during the rotation of the producer body
127 relative to the ash pan upon the column of
128 ashes within the apron supported by the ash
129 receptacle.
- 130 28. In a gas producer, a rotatable producer
131 body, a rotatable ash receptacle beneath the
132 body and movement imparting and control-
133 ling means which causes the body and recep-
134 tacle to rotate at times at substantially the
135 same speed and at times relatively with one
136 part rotating a definite amount faster than
137 the other.
- 138 29. In a gas producer, a producer body,
139 an ash receptacle beneath the same, both
140 mounted for rotary movement and one ro-
141 tatable with reference to the other, and

mechanical means for causing both the body and receptacle to be rotated when the producer is in operation, with one part making a definite number of revolutions less than ⁵ the number of revolutions made by the other part during the same time.

30. In a gas producer, the combination with a fuel section and an ash pan, of means for imparting rotation to both of said parts

in the same direction but at different speeds, ¹⁰ said means including mechanism for permitting rotation of both parts at the same speed in consequence of the friction of the contained bed of fuel.

In testimony whereof, I hereunto affix my ¹⁵ signature.

JOHN F. ROGERS.
